J. F. FISHER

WHEEL PIT

Filed Dec. 12, 1924

INVENTOR:
John F. Fisher
BY T. H. Gibbs
ATTORNEY.

UNITED STATES PATENT OFFICE.

JOHN FREDERICK FISHER, OF ST. LOUIS, MISSOURI, ASSIGNOR TO AMERICAN CAR AND FOUNDRY COMPANY, OF NEW YORK, N. Y., A CORPORATION OF NEW JERSEY.

WHEEL PIT.

Application filed December 12, 1924. Serial No. 755,488.

To all whom it may concern:

Be it known that I, JOHN F. FISHER, residing at St. Louis, Missouri, and being a citizen of the United States, have invented 5 certain new and useful Improvements in a Wheel Pit, of which the following is a full, clear, and exact description, such as will enable others skilled in the art to which it appertains to make and to use the same, 10 reference being had to the accompanying drawings which illustrate the preferred form of the invention, though it is to be understood that the invention is not limited to the exact details of construction shown 15 and described, as it is obvious that various modifications thereof within the scope of the claims will occur to persons skilled in the art.

In said drawings:

20 Figure 1 is a view partly in vertical section and partly in elevation of a wheel pit constructed in accordance with this invention, and

25 Figure 2 is a horizontal section of the wheel pit taken along line 2—2 of Fig. 1, the wheels being omitted.

It is an object of this invention to provide an improved cooling pit for cast car wheels, and more particularly to provide a 30 pit of the type described wherein provision is made for setting up a circulation of air within the pit so that the top wheel in the pit will cool uniformly with the rest of the wheels in the pit.

35 Another object of the invention is to provide a pit, which is so constructed that the guide flanges of the wheels may be positioned close to the enclosing wall of the pit and relatively small pockets provided be- 40 tween the wall of the pit and tread portions of the wheels, so that air, which will be comparatively still, will accumulate in these pockets and assist in causing the wheels to be uniformly cooled.

45 Another object of the invention is to provide a pit which may be closed and thus prevent outside air from entering the pit and mixing with the air circulating in the pit during the cooling of the wheels.

50 Another object of the invention is to provide a pit in which a stack of wheels may be supported in the pit in proper spaced relation to the top and bottom of the pit, to permit the air to pass upwardly through 55 the hub portions of the wheels and down-

wardly through air ducts provided in the enclosing wall of the pit.

This improved pit is to be disposed vertically and is provided with an outer casing which is cylindrical in shape and provided with a bottom 1 and an annular wall 2. This casing is open at its upper end and at its open upper end is provided with a collar 3 which rests upon the upper edge of the casing and is provided with a depending retaining flange 4 which holds the collar in proper position upon the casing. An annular groove or seat 5 leads from the upper face of this collar to receive the depending flange 6 of the cover 7 which will be put in place to close the pit at its upper end after the wheels have been put in place within the pit.

The bottom 1 of this casing is covered by a flooring 8 which is formed of tiles put in place, as shown in Figs. 1 and 2. At the center of the flooring there has been provided a block 9 which tapers upwardly, as shown in Fig. 1, and carries posts 10 which extend upwardly from the block in spaced relation circumferentially thereof. These posts extend above the upper end of the block and are so spaced in relation to each other that when the wheels are put in place within the pit, the lower wheel will have 85 its hub portion resting upon the upper ends of the posts. The stack of wheels will therefore be supported in the pit in spaced relation to the flooring 8 so that air can pass between the posts and upwardly through a 90 flue or duct formed by the axle receiving openings in the hubs of the stack of wheels.

The annular wall 2 of the casing is also provided with a lining which provides an enclosing wall for the stack of wheels. This 95 lining is formed of blocks 11 which are ar- cuate in shape, as shown in Fig. 2. The blocks will be formed of any suitable material and will each be provided intermediate its length with an opening 12 and at its 100 ends with grooves 13. When the blocks are put in place to form the enclosing wall or lining the end grooves of each tier of blocks will cooperate to provide openings similar to the openings 12 and when the wall is 105 completely built, these openings in the tiers of blocks will cooperate to provide air ducts which extend vertically through the enclos- ing wall. These air ducts are open at their upper ends and are also open at their lower 110

ends. It should be noted, however, that the blocks 14 which form the base of the enclosing wall and rest upon the flooring 8 have the openings 15 formed to provide outlet mouths for the ducts which are disposed at a downward and inward incline, as shown in Fig. 1, and therefore sand and other foreign matter will not collect at the lower ends of the ducts but will pass out of these ducts and on to the flooring 8 where it can be readily removed. The shape of the block 9 also serves to cause sand and other foreign matter such as scale from the cooling wheels to move on to the flooring 8 to such a point that it can be readily removed. The wheels are to be properly centered in the pit with their hubs disposed above the posts 10 and the guide flanges in slightly spaced relation to the enclosing wall formed of the blocks, and therefore at points spaced circumferentially of the enclosing wall there has been provided spacing strips 17 formed of metal and secured in place between certain of the blocks, as shown in Fig. 2, with their edge portions extending beyond the inner face of this enclosing wall. These protruding portions of the strips 17 can therefore serve to engage the guide flanges of a stack of wheels and retain the wheels properly stacked one upon another and in proper spaced relation to the inner face of the enclosing wall.

When this pit is in use, a stack of wheels will be lowered into the pit with the hub portion of the lower wheel resting upon the posts 10. In the preferred manner the wheels will be lowered one at a time and the stack built within the pit, but if desired, the wheels may be stacked outside of the pit and the entire stack lowered at one time. After the stack has been built in the pit, the cover 7 will be put in place and as the hub portions of the wheels contain a greater mass of metal, an air circulation will be set up within the pit, as indicated by the arrows in Fig. 1. This air passes upwardly through the flue or duct formed by the axle receiving openings in the hubs of the wheels and when the air reaches the top of the pit, it will then move towards the side walls thereof above the upper end of the lining or enclosing wall and pass downwardly through the ducts formed in this enclosing wall. These ducts formed in the enclosing wall will have a combined capacity approximately the same as the capacity of the duct or flue formed by the wheel hubs and therefore a free circulation will be permitted. A certain amount of air passes into the space between the tread portions of the wheels and the inner face of the enclosing wall. This air will circulate in the pockets formed between the guide flanges of the wheels in the form of eddies, as indicated by the arrows in Figure 1, and this air

about the tread portions of the wheels will therefore be practically still air and will serve to cause the tread portions of the wheels to cool at approximately the same rate as the hub portions. It will therefore be seen that with this improved pit the wheels will be evenly cooled at all points and a very strong wheel produced.

What is claimed is:

1. In a wheel cooling pit, an enclosing wall having air ducts therein open at the top and bottom, and a supporting block for receiving the wheel hubs having passages for directing the air currents to the axle bores of the wheel hubs.

2. In a wheel cooling pit, an enclosing wall having air ducts therein open at the top and bottom, a supporting block for receiving the wheel hubs and guides for the wheels mounted in said enclosing wall.

3. In a wheel cooling pit, an enclosing wall having air ducts therein, a casing enclosing said wall, a supporting block for receiving the wheel hubs and a cover for said pit carried by said casing and spaced from the top of said wall.

4. In a wheel cooling pit, an enclosing wall having air ducts therein open at their upper and lower ends for communication with the upper and lower portions of the pit and having a combined air capacity corresponding to that of an axially disposed air passage provided by the hubs of wheels stacked in the pit and supported in spaced relation to the top and bottom of the pit.

5. In a wheel cooling pit, an enclosing wall providing the pit with an interior diameter slightly greater than the external diameter of a stack of wheels at the guide flanges of the wheels, said wall having air ducts opening through its upper and lower ends for communication with the top and bottom of the pit, and means for supporting a stack of wheels in the pit and permit air to pass through the axle receiving hub openings of the wheels.

6. In a wheel cooling pit, an enclosing wall providing the pit with an interior diameter slightly greater than the external diameter of a stack of wheels at the guide flanges of the wheels, said wall having air ducts opening through its upper and lower ends for communication with the top and bottom of the pit, and means for supporting a stack of wheels in said pit in spaced relation to the top and bottom of the pit.

7. A wheel cooling pit having a bottom, an enclosing wall, and a cover for closing the pit at its upper end and shutting off communication with the outer atmosphere, said wall having vertically disposed air ducts open at their upper and lower ends for communication with the upper and lower end portions of the pit, and means for supporting a stack of wheels in the pit in

spaced relation to the top and bottom of the pit and permitting air to pass through the hub portions of wheels stacked in the pit.

- 5 8. A wheel cooling pit having a bottom, an enclosing wall, and a cover for closing the pit at its upper end and shutting off communication with the outer atmosphere, vertical air ducts being provided about the enclosing wall and communicating with the upper and lower ends of the pit, and means for supporting a stack of wheels in the pit in spaced relation to the top and bottom of the pit.
- 10 9. A wheel cooling pit having a bottom, an enclosing wall, and a cover for closing the pit at its upper end and shutting off communication with the outer atmosphere, vertical air ducts being provided about the enclosing wall and communicating with the upper and lower ends of the pit, means for supporting a stack of wheels in the pit in spaced relation to the top and bottom of the pit, and including upwardly extending
- 15 20 25 posts for engaging the lower wheel in spaced relation to each other circumferentially of the wheel.

10. A wheel cooling pit having a bottom, an enclosing wall provided with air ducts opening through its upper end for communication with the upper portion of the pit and having their lower ends opening through the inner face of the wall adjacent the bottom and at their open lower ends having faces extending downwardly at an inward incline, and means extending upwardly from said bottom for supporting a stack of wheels in the pit in spaced relation to the bottom.

11. A wheel cooling pit having a bottom and an enclosing wall, vertically disposed air ducts being provided about the wall and open at their upper and lower ends for communication with the upper and lower portions of the pit, and means for supporting a stack of wheels in said pit, said means comprising a block disposed axially of the pit upon the bottom and tapered upwardly, and posts extending upwardly from said block in spaced relation circumferentially thereof for engaging the lower wheel of a stack.

In witness whereof I have hereunto set my hand.

JOHN FREDERICK FISHER.
